UNITED STATES PATENT OFFICE.

CARL G. OSTEMAN, OF BOSTON, MASSACHUSETTS, ASSIGNOR TO S. A. WOODS MACHINE COMPANY, OF BOSTON, MASSACHUSETTS, A CORPORATION OF MASSACHUSETTS.

CHIP BREAKER FOR WOODWORKING MACHINES.

1,404,402.

Specification of Letters Patent. Patented Jan. 24, 1922.

Application filed May 2, 1921. Serial No. 466,201.

To all whom it may concern:

Be it known that I, CARL G. OSTEMAN, a citizen of the United States, and a resident of Boston, in the county of Suffolk and

5 State of Massachusetts, have invented an Improvement in Chip Breakers for Woodworking Machines, of which the following description, in connection with the accompanying drawings, is a specification, like 10 characters on the drawings representing like parts.

This invention relates to wood working machines such as planers and matchers and has more particularly to do with the construction of the chip breaker. One object 15 of my invention is to provide means for applying a variable tension to the chip breaker. Another is to provide a construction of chip breaker, however tensioned, 20 which will prevent it from engaging the cutter head if unduly displaced.

My invention will best be understood by reference to the following description of an illustrative embodiment thereof shown by 25 way of example in the accompanying drawings, wherein:

Fig. 1 is a partial side elevation of a planer showing such parts as are required for an understanding of my invention;

30 Fig. 2 is a section on the line 2—2 of Fig. 1, with parts broken away;

Fig. 3 is a section on line 3—3 of Fig. 2; and

Fig. 4 is an elevation of the chip breaker 35 yoke and its supporting means as seen from the right in Figs. 1 and 3.

Referring to the drawings I have there 40 shown a portion of the main frame or bed 3 of a planer or like machine on which is mounted the cutter head stand 5 receiving the vertically adjustable cutter head slide 7 supporting at its upper end the cutter head yoke and the top cutter head 9 the latter being indicated in dotted lines in Fig. 1.

45 In the embodiment of my invention here shown the chip breaker cooperating with the head 9 is supported by links 11 from upstanding ears 13 at the upper end of the cutter head slide, these links supporting the chip breaker yoke 15 at either side of the latter as best shown in Fig. 2. On this yoke 50 are carried the individual shoes 17 which may be provided with rearwardly extending stems 19 by which they are secured in the slotted members 21 vertically adjustable on

the cross bar of the yoke 15 as indicated in the drawings. This construction may be varied in accordance with known principles of design as may be desired.

The shoes 17 bear with considerable 60 weight on the work passing through the machine but under certain circumstances it is desired to increase this force by exerting an additional tension on the chip breaker and on the other hand in the case of very light 65 stock it may be desirable sometimes to counterbalance the chip breaker so that the force that it will exert will be less. In the present instance means are provided for exerting a variable tension on the chip breaker either 70 to weight or to counterbalance the same comprising mechanism received below the chip breaker proper and conveniently provision is made for adjusting the tensioning mechanism from a convenient position at the 75 side of the main frame of the machine. In the present embodiment of my invention, as best shown in Fig. 2, I provide at either side of the yoke 15 depending connecting rods 23 by which the yoke may be moved up and 80 down. Herein the lower ends of the rods 23 are supported by arms 25 substantially parallel to the links 11 and carried on the rock shaft 27 journaled at the lower end of the cutter head slide 7. It will be understood that if the arm 25, referring to Fig. 1, 85 is rocked clockwise a downward force will be exerted on the chip breaker shoes 17 and, on the contrary, if it is rotated counterclockwise a lifting, counterbalancing movement will be effected. Herein I have shown a lever arm 29 secured to the rock shaft for operating the same, the arm 29 and the arms 25 constituting in effect a bell crank, one arm of which is secured to the connecting 90 rods 23 and through the other arm of which force is applied.

It will be noted that the parts so far mentioned are all mounted and connected with the cutter head slide to move vertically 100 therewith in the adjustment of the cutter head. The tension applying mechanism on the contrary is in a fixed position but is connected to the parts already described in such manner that motion due to adjustment 105 of the cutter head slide does not substantially effect movement of the parts. Herein, as best shown in Fig. 1, a relatively long connecting link 31 connects the crank arm 29 to crank arm 33 substantially parallel 110

thereto. In other words, the arm 33 may be designed to be strictly parallel to the arm 29 in the average median position of the latter due to adjustment of the cutter head 5 slide. The arm 33 is carried by a short rock shaft 35 projecting through the side frame 3 of the machine so that adjustment of the force exerted on the cutter head is conveniently provided for exteriorly of the 10 machine and at the side thereof.

Referring to the drawings, the rock shaft 35 is herein operated by lever 37 having the handle 39 for moving the same, the lever preferably extending on both sides of the 15 pivotal point of the shaft 35 and means are provided for adjustably connecting, tension applying means to the lever. Herein a suitable coil spring 41 anchored at one end of the frame of the machine is used and the other 20 end of the spring is secured to the slide block 43 longitudinally adjustable in the slot 45 extending along the lever, at any point of which it may be clamped in well known manner. When the block 43 is at the right 25 of the pivotal point 35, referring to Fig. 1, the lever 37 is drawn against a suitable stop 47 and it will be clearly seen from Fig. 1 the effect of the operation of the spring is to exert a downward pressure on the chip 30 breaker through the connecting rods 23 and this pressure will vary in accordance with the position of the block 43 in the slot 45. If the block 43 is in the line between the pivotal point 35 and the anchored end of the 35 spring the tension of the spring will have no effect on the chip breaker which will rest on the work with its own weight. On the other hand, if the block 43 is shifted to the left of the point 35 the spring will have a variable 40 counterbalancing effect on the chip breaker, exerting a lifting force through the connecting rods 23.

For holding the chip breaker in elevated position during adjustment of the machine 45 a pivoted latch 49 may be provided cooperating with the lever 37. The latch 49 is normally supported in the position shown in Fig. 1 by stop pin 51 and as seen from that figure if the lever 37 is swung up by a considerable depression of the handle 39, it will 50 throw up the latch 49 which will swing back by gravity underneath the lever and serve to hold the same in elevated position against the force of spring 41 until the lever is 55 again elevated by means of the handle 39 and the latch 49 manually displaced.

A feature of the construction shown in the drawings is the provision of means whereby the chip breaker, whether tensioned 60 as here shown, or otherwise is prevented from coming into contact with the cutter head if it is accidentally displaced beyond its normal range of movement. The shoes 17 of the chip breaker rising and falling might, 65 under certain circumstances, be unduly lifted

and would come into contact with the cutter head. I herein provide means whereby when a certain limited range of displacement is exceeded the chip breaker mechanism is moved rectilinearly and conveniently in an upward diagonal direction bodily away from the vicinity of the cutter head and after the disturbing condition has ceased it will be automatically returned to its ordinary operating position.

Referring particularly to Figs. 1 and 3 I herein show an arrangement whereby the chip breaker yoke 15 with the members carried thereby and the suspending links 11 will be bodily shifted upwardly and toward the right on excessive movement of the yoke. To effect this the links 11 may be connected to the ears 13 by pin and slot connections, conveniently formed as shown by means of the transversely extending open ended slots 51 in the links hooking over the pins 53 projecting from the ears 13. Normally pin 53 rests in the upper end of the slot as shown and the link and pin act as if the link were mounted on an ordinary pivot suspending the cutter yoke so that it swings in its ordinary operation through a limited arc around the center 53. If, however, the shoes 17 are unduly lifted so that there would be danger of bringing them into contact with the cutter head 9 I provide means for interengaging the yoke and links so that they move as a unit and the links will slide over the pins 53, the pins moving downwardly in the slots 51, and the whole chip breaker and its suspending mechanism will be shifted bodily away from the cutter head, guided diagonally by the walls of the slots. This action may be conveniently effected by providing pins 55 projecting from the side of the links and overhanging a portion of the chip breaker yoke. The yoke normally has lost motion relative to the pins but on excessive lifting movement of the chip breaker it will come in contact with the pins and on further movement the links 11 will lift bodily with the chip breaker and the whole will be displaced to the right guided by the diagonally extending slot.

Pins 57 may be provided on the chip breaker yoke overhanging the links 11 so that as the chip breaker falls again under gravity the links will be pushed downwardly to bring the pins 53 to the upper ends of the slots as shown in Fig. 1. The chip breaker and links have a relative lost motion between the two positions where the pins 55 on the one hand and the pins 57 on the other engage to interlock them for movement in one or the opposite direction, respectively.

Having thus described in detail the particular embodiment of my invention shown by way of example in the accompanying drawings, the principles exemplified thereby which I claim as new and desire to secure

by Letters Patent I shall express in the following claims:

Claims:

1. In a machine of the class described a chip breaker and means for tensioning the same comprising a connecting rod depending therefrom, a lever at the side of the machine for operating said rod and force applying means adjustably connected to the lever.
2. In a machine of the class described a chip breaker and means for tensioning the same comprising mechanism received beneath the same and adjustably operable exteriorly from the side of the machine.
3. In a machine of the class described a chip breaker and means for tensioning the same comprising a connecting rod depending therefrom and means exteriorly mounted at the side of the machine frame for applying an adjustably variable force to said rod.
4. In a machine of the class described a lever pivoted at the side of the machine, a stop cooperating therewith, a block slideable along the lever, a tension spring connected to the block, a chip breaker and a force transmitting connection between the chip breaker and the lever.
5. In a machine of the class described a lever pivoted at the side of the machine, a stop cooperating therewith, a block slideable along the lever, a tension spring connected to the block, a catch for latching up said lever, a chip breaker and a force transmitting connection between the chip breaker and the lever.
6. In a machine of the class described in combination with the cutter head slide, links pivoted thereto, a chip breaker supported by said links, a connecting rod depending from the chip breaker, a bell crank on said slide having an arm connected to the rod and an adjustable tension-applying means connected to said other arm.
7. In combination with a chip breaker yoke, links suspending the same and having a shiftable pivot, and means for interengaging said yoke and the links on excessive movement of the yoke to shift the pivot of the latter.
8. In combination with a chip breaker yoke, links pivoted to the same having trans-
- versely slotted ends, supports received in the slots and means whereby on excessive movement of the yoke said links are shifted by movement of said ends over the supports. 55
9. In combination with a chip breaker yoke, links pivoted to the same having transversely slotted ends, supports received in the slots and means for interengaging the yoke and the links on excessive lifting of the former to shift the links by movement of said ends over the supports whereby to move the yoke bodily away from the cutter head. 60
10. In combination with a chip breaker yoke, links pivoted to the same having transversely slotted ends, supports received in the slots, means for interengaging the yoke and the links on excessive lifting of the former to shift the links by movement of said ends over the supports whereby to move the yoke 70 bodily away from the cutter head and means normally interengaging under gravity to cause the yoke to move said ends down over said supports. 65
11. In combination with a chip breaker yoke, suspension links therefor having transverse pin and slot connection with a support, a force closure connection against downward movement of said yoke relatively to the links normally to maintain the pin in 80 one end of the slot to serve as a pivot and a force closure connection effective on excessive upward movement of the yoke to interlock the same with the links for further upward movement. 75
12. In combination with a chip breaker yoke, suspension links therefor having transverse pin and slot connection with a support and lost motion interengaging means between said yoke and said links, effective to 90 cause both to move upwardly and downwardly as a unit at the extremes of such motion. 85
13. In combination with a chip breaker mounted for limited oscillating movement, 95 diagonal guide surfaces effective when the chip breaker passes an extreme of such movement to shift it bodily laterally.

In testimony whereof, I have signed my name to this specification.

CARL G. OSTEMAN.
